UNITED STATES PATENT OFFICE.

DANIEL KOPS, OF NEW YORK, N. Y.

BRASSIÈRE.

1,252,124.

Specification of Letters Patent.

Patented Jan. 1, 1918.

Application filed May 7, 1917. Serial No. 186,835.

To all whom it may concern:

Be it known that I, DANIEL KOPS, a citizen of the United States, residing in the borough of Manhattan, city, county, and 5 State of New York, have invented an Improvement in Brassières, of which the following is a specification.

My present invention relates to a brassière particularly adapted for use in connection with low-busted corsets and by stout 10 women. As is understood by those acquainted with the art, at the present time, the low-busted corset is in general use due largely no doubt to the prevailing fashions. 15 In the use of low-busted corsets, particularly by stout women, there is a tendency to develop a roll or layer of flesh between the busts and the upper front edge of the garment, and oftentimes this is developed to 20 such an extent as to be inconvenient and also to produce an undesirable break in the otherwise regular contour of the body of the wearer. The object of my present invention is the provision of a brassière or 25 brassière attachment so constructed that when in use it will obviate the difficulty to which reference is hereinbefore made and will reduce if not entirely eliminate the roll of flesh produced at the top edge of the cor- 30 set and in all events will make the same un- observable through an outer garment by making the contour of the body of the wearer symmetrical. In carrying out this invention the brassière attachment com- 35 prises a pad adapted at one edge to be connected to the lower front edge of the body of the brassière and to extend upwardly therefrom. This brassière pad is preferably triangular in cross-section and is suitably 40 provided with stays or stiffeners to accom- plish the purpose hereinbefore ascribed to it.

In the drawing:

Figure 1 is an interior elevation showing 45 a brassière made in accordance with this invention.

Fig. 2 is an elevation showing the garment in use on the body, and

Fig. 3 is an elevation showing a modified 50 form of the pad member employed in connection with the brassière.

Referring to the drawing, the brassière made in accordance with this invention preferably comprises a body indicated at 55 10 and is so constructed as to be closed at the front and to be opened at the back at which

the parts are connected after being placed on the body of the wearer. The body of the brassière may be suitably stiffened by sets of stays placed on both sides of the medial 60 line of the garment. Those in the front are indicated at 11 and those in the back are indicated at 12, although as will be understood, the manner in which the garment is provided with stays or stiffeners forms no 65 part of the present invention. Also as indicated in Fig. 1, at one end of the body of the brassière the same is fitted with a series of hooks 13 and at the other end with a corresponding series of eyelets 14 adapted to 70 be engaged by the hooks so as to connect the parts of the garment for use on the body of the wearer. Also in the back of the garment I may employ one or more strips of yielding material, such for example as elastic fabric indicated at 15 for the purpose of yieldingly maintaining the garment on the body of the wearer. Furthermore as shown in this figure the brassière body is also suitably fitted with shoulder strips 16. 80

In connection with the brassière as hereinbefore described or of any other construction, I employ a pad indicated at 17. This pad comprises a body member preferably triangular in configuration and fitted with a 85 series of stays 18 as indicated in Fig. 1 running substantially from the apex of the triangle to the base thereof and therefore being in a central position and extending longitudinally of the body of the wearer when 90 in use. As shown in Fig. 3 the pad member may also be provided with suitable stays or stiffeners 19 running along the opposite edges thereof. This pad member 17 as shown in Fig. 1, is preferably secured to the 95 brassière by having the base of the pad connected to the lower central portion of the front edge of the brassière along a line of sewing 20, although as will be understood the pad may be entirely separated from the 100 brassière and connected thereto at this position in any desired manner, when however the pad is secured by sewing the base thereof to the lower front edge of the brassière, the side edges, for a short distance above the 105 base, are also secured to the body of the brassière along lines of sewing indicated at 21 and 22 on the opposite sides of the pad.

When in use as will be understood, the lower edge of the brassière overlaps the upper edge of the corset garment and the pad stayed or stiffened as hereinbefore described

will prevent the tendency to produce the roll of flesh between the busts and the upper edge of the corset, or when this effect has been produced, the pad will control and tend to eliminate the same.

I claim as my invention:

1. As a new article of manufacture, a brassière comprising a body member, a substantially triangular shaped pad independent of the brassière body member, stays secured in the pad and extending approximately from the apex to the base line thereof, the said pad being adapted to be secured along its base line to the lower front portion of the brassière body member.

2. As a new article of manufacture a brassière pad comprising a substantially triangular body member, stays extending approximately from the apex thereof to the

base line in a central position, and stays also secured in the opposite inclined edges thereof, the said brassière pad being adapted to be secured at its lower side to the lower front portion of a brassière.

3. As a new article of manufacture a brassière comprising a body member, a substantially triangular shaped pad, stays secured in the pad extending approximately from the apex to the base line thereof in a central position, and stays also secured in the pad along the inclined edges thereof, the said pad being independent of the brassière body member and adapted to be secured at its lower side to the lower front portion of the brassière body member.

Signed by me this 2nd day of May, 1917.

DANIEL KOPS.
